(57) **CLAIM**

The ornamental design for a display screen with graphical user interface, as shown and described.

DESCRIPTION

FIG. 1 is a front view of a first embodiment of a display screen with graphical user interface, showing our new design;

FIG. 2 is a front view of a second embodiment of a display screen with graphical user interface, showing our new design; and,

FIG. 3 is a front view of a third embodiment of a display screen with graphical user interface, showing our new design.

The broken lines showing a display screen and elements of the graphical user interface illustrate portions of the article, and form no part of the claimed design.

1 Claim, 3 Drawing Sheets
